UNITED STATES PATENT OFFICE

FRANZ O. MATTHIESSEN, OF IRVINGTON, NEW YORK.

PROCESS OF REMOVING THE IMPURITIES OF RAW SUGAR.

SPECIFICATION forming part of Letters Patent No. 329,331, dated October 27, 1885.

Application filed July 3, 1885. Serial No. 170,597. (No model.)

To all whom it may concern:

Be it known that I, FRANZ O. MATTHIESSEN, of Irvington, New York, have invented certain Improvements in Processes of and Apparatus 5 for Removing the Impurities from Raw Sugar, of which the following is a specification.

In certain processes of manufacturing refined cane-sugar heretofore practiced the raw sugar is first washed, by which some of its impurities are removed, and is then dissolved in water and filtered through bag-filters, by which other impurities are removed preparatory to the filtration of the sugar solution through bone-black. The syrup resulting from the 15 washing of one lot of raw sugar is sometimes repeatedly used for mixing with other lots of raw sugar to prepare them for washing, as described in Letters Patent of the United States No. 191,539, issued to Franz O. Matthiessen, June 5, 1877, according to which the syrup is used over and over for mixing with raw sugar until it becomes so charged with impurities that it ceases to be useful for that purpose. Some raw sugars of high grade contain so small a proportion of impurities that they do not require to be washed, but may at once be dissolved in water and filtered through filter-bags for the removal of their mechanical impurities preparatory to filtration through 25 bone-black. By the present invention, in the process of refining raw sugar, the preliminary filtration through bag-filters is dispensed with, and the mechanical impurities are removed from the raw sugar by mechanical means in connection with the bone-black filter itself, and while the process of filtration through bone-black is being continuously carried on. The process embraces the following steps: First, the raw sugar, if of low grade, is washed 35 to remove a portion of its impurities; secondly, the washed sugar is dissolved in water, or, if of high grade, the raw sugar is dissolved in water without having been previously washed. Next, the sugar solution 40 obtained in either of these ways, instead of being filtered through bag-filters, is at once filtered through bone-black by the process of upward filtration through a column of bone-black contained in a filtering-chamber provided at the bottom with a scraper or dis- 45 charger for removing the successive strata

from the base of the column with which the sugar solution first acquires contact as rapidly as may be required by the exhaustion of the decolorizing power of the bottom stratum and 55 the presence of mechanical and other impurities which may collect at that point.

Any suitable apparatus may be employed for washing the raw sugar—such as, for example, that described in Letters Patent of the 60 United States No. 303,443, dated August 12, 1884, granted to F. O. Matthiessen and George Dinkel. Starting with a raw sugar from which a portion of the impurities has been removed by washing, or with a raw sugar containing 65 only a moderate proportion of impurities, which, therefore, has not needed washing, the raw sugar is dissolved in water, forming a solution of, say, 30° Baumé, and then filtered upwardly through bone-black contained in a 70 filtering-chamber provided at the bottom with a scraper or other instrumentality, which, by its operation while the process of filtration is being continuously carried on, gradually removes the exhausted bone-black and the impurities which collect at the place where the sugar solution is first brought into contact with the bone-black. The syrup resulting from the washing of the raw sugar may also be diluted with water and filtered in the same 75 way. The speed with which the scraper or other discharging instrumentality is operated for the removal of the impurities and exhausted bone-black from the filtering-chamber will of course be varied according to the quantity, 80 and also according to the character of the impurities present in the solution which is to be filtered.

Among the mechanical impurities present in raw sugar are sand, clay, and sometimes fiber. 90 A certain portion of them having, when necessary, been removed by washing the raw sugar, the remainder is removed by the bone-black, and is collected with the exhausted bone-black discharged by the scraper or dis- 95 charger from the surface of the mass of bone-black with which the sugar solution is first brought into contact. Similarly the impurities contained in the syrups produced by washing the raw sugar are removed by diluting the 100 syrup and filtering it through a bone-black filter provided with a scraper or discharger,

and it therefore results that the impurities from the raw sugar are concentrated in a comparatively small quantity of bone-black—that is, the exhausted bone-black which is removed from time to time or continuously by the operation of the discharging instrumentality.

By means of the improved apparatus forming part of the present invention provision is made for carrying on a continuous decolorizing operation, in which all the sugar-liquor which is forced through the filtering-chamber is subjected to uniform conditions with respect to the duration of its contact with a fixed quantity of bone-black, the decolorizing power of which is maintained substantially unchanged by the gradual removal of the exhausted bone-black and collected impurities from the bottom of the filtering-chamber and the concurrent feeding of fresh bone-black into the top of the filtering chamber.

In its essential features the apparatus consists of, first, a filtering-chamber into the top of which the fresh bone-black is fed as required; secondly, a supporter and discharger or scraper for supporting the column of bone-black contained in the filtering-chamber, and for effecting at a prescribed rate the gradual removal of bone-black from the base of the column as the bone-black at that point becomes exhausted and charged with impurities separated from the sugar-liquor which enters the filtering-chamber at the bottom; thirdly, a receiving-chamber beneath the filtering-chamber for receiving the exhausted bone-black and collected impurities discharged from the filtering-chamber; fourthly, means for removing the exhausted bone-black and collected impurities from the receiving-chamber; and, finally, a conduit for introducing into the receiving-chamber under suitable pressure the sugar-liquor which is to be decolorized, and an outlet or outlets for the discharge from the upper part of the filtering-chamber of the sugar-liquor which has been forced upward through so much of the column of bone-black as is below the level of the said outlet or outlets.

The supporter and discharger constitutes the movable bottom of the filtering-chamber, and is a diaphragm provided with perforations or slots of such shape and dimensions that while they will not permit the superincumbent bone-black to fall through them continuously under the influence merely of its own gravity, they will serve, when the diaphragm is appropriately moved, to effect the removal and discharge from the base of the column of a stratum of bone-black of prescribed thickness.

The accompanying drawings, illustrating the said improved apparatus, are as follows:

Figure 1 is a central vertical section of the filtering-chamber, the receiving-chamber, and other appendages of the apparatus. Fig. 2 is a horizontal section taken through the line

xx on Fig. 1, affording a top view of the movable diaphragm, which constitutes the movable bottom of the filtering-chamber, and which by reason of its functions is herein called the "supporter and discharger" or "scraper." Fig. 3 is a vertical section of the scraper, taken through the line *yy* on Fig. 2.

The apparatus represented in the drawings consists, substantially, of a vertical cylinder, A, for containing a column of bone-black, B, a movable slotted diaphragm or scraper, C, and a receiving-chamber, D, having an inclined bottom, D', by means of which the exhausted bone black and impurities removed by the scraper are conducted by their own gravity into the bottom of the well E, from which they are elevated by means of the bucket and chain elevator E', and are discharged at the mouth of the well upon the inclined chute E''. The saccharine liquor to be decolorized is introduced into the well by means of the pipe F from a suitably elevated reservoir. The sugar-liquor thus introduced falls into the bottom of the well, and rises by hydrostatic pressure through the mass of bone-black, B, contained in the filtering-chamber, and escapes therefrom through the perforations G in the side wall of the cylinder A into the external trough, G', from which it is conducted to a suitable depository by the discharge-pipe G''. The scraper C is circular, and is of larger diameter than the cylinder A, so that its rim C' is contained within the circumferential enlargement A' of the cylinder A. The rim C' is supported upon the conical rollers H H, &c., which are provided with suitable bearings in standards erected within the enlargement A' of the cylinder A. The scraper is affixed to the vertical shaft I, the lower end of which is provided with a bearing arranged upon the horizontal beam I', having its central portion supported by the inclined braces I'' and I'''. The shaft I is provided with a bearing, *i*, at the top of the cylinder A, and has affixed to its upper end a driving-pulley or toothed wheel, *i'*, to which power is applied to rotate the scraper. The scraper is provided with radially-slotted openings C' C', &c. The upper edges, *c* and *c'*, of the side walls of each of the slots C' form, respectively, the one an acute and the other an obtuse angle with the uppersurface of the diaphragm, substantially as shown in Fig. 3. The acute edge *c* is the cutting-edge, and, being somewhat higher than the obtuse angle *c'*, operates, when the scraper is rotated, to cut away from the base of the column of bone-black a helical chip or shaving of uniform thickness, which falls down the inclined bottom D' of the receiving-chamber D to the bottom of the well E, and is caught and carried upward by the buckets *e* *e*, &c. The buckets *e* *e*, &c., are made of wire-gauze, or are finely perforated, and the well-tube is prolonged considerably above the level of the mouth of the inlet-pipe F, in order that the sugar-liquor may have an opportunity to drain out of the

buckets during the latter part of their upward journey before they discharge their contents upon the chute E.

What is claimed as the invention is—

- 5 1. The herein-described process of removing the impurities from raw sugar, the same consisting in dissolving the raw sugar in water, then filtering it by forcing it upward through bone-black, and by means of a scraper or dis-
- 10 charger gradually removing the collected impurities and exhausted bone-black from the bottom of the mass of bone-black contained in the filtering-chamber through which the sugar-liquor is forced.
- 15 2. In apparatus for effecting the decolorization of sugar-liquor by the process of upward filtration through bone-black, the com-

bination, as herein set forth, of a filtering-chamber having a movable bottom for supporting the column of bone-black contained in the filtering-chamber, and for gradually removing the bone-black from the bottom of said column, a receiving-chamber for receiving the bone-black so removed from the filtering-chamber, and means for removing the bone-black from the receiving-chamber without interrupting the upward flow of the sugar-liquor through the column of bone-black to outlets provided for its exit from the filtering-chamber.
